UNITED STATES PATENT OFFICE.

OSCAR A. TAFT, OF LEOMINSTER, MASSACHUSETTS.

DESIGN FOR A BASE FOR BOOT-CLEANERS.

SPECIFICATION forming part of Design No. 33,485, dated October 30, 1900.

Application filed August 24, 1900. Serial No. 27,963. Term of patent 8½ years.

To all whom it may concern:

Be it known that I, OSCAR A. TAFT, a citizen of the United States, residing at Leominster, in the county of Worcester and State of Massachusetts, have invented and produced a new and original Design for the Bases of Boot-Cleaners, of which the following is a specification, reference being had to the accompanying drawings, forming a part thereof.

In the drawings, Figure 1 is a plan view showing my new design; and Fig. 2 is a side or edge view thereof, partly in section, on line 2 2 of Fig. 1.

As shown in the drawings, the leading or

material feature of my design consists of a 15 saucer-like receptacle A, with upwardly-curved edges provided with concave recesses B, adjacent to which are curved raised ribs C. The receptacle A has a raised central portion D. 20

I claim—

The design for a base for boot-cleaners, as herein shown and described.

OSCAR A. TAFT.
